PAGE 2

Fig-3

FIG-4FIG-5

FIGURE 1 is a front perspective view of a vacuum leaf loader for a vehicle embodying our new design;

FIGURE 2 is a side elevational view thereof on a reduced scale;

FIGURE 3 is a perspective view thereof showing the front and side opposite that shown in FIGURE 1;

FIGURE 4 is a perspective view of a modified form of the vacuum leaf loader for a vehicle shown in FIGURE 1; and

FIGURE 5 is a side elevational view thereof on a reduced scale.

The broken line showing is for illustrative purposes only.

We claim:

The ornamental design for a vacuum leaf loader for a vehicle, substantially as shown and described.
